Primary Examiner — Kevin K Rudzinski*Assistant Examiner* — Paul D Bohannon(74) *Attorney, Agent, or Firm* — Banner & Witcoff, Ltd.(57) **CLAIM**

The ornamental design for a chair, as shown and described.

DESCRIPTION

FIG. 1 is a perspective view of a chair showing my new design;

FIG. 2 is a top plan view thereof;

FIG. 3 is a front view thereof;

FIG. 4 is a left side view thereof, the right side view being a mirror image thereof; and,

FIG. 5 is a rear view thereof.

The broken lines illustrate portions of the chair that form no part of the claimed design.
